UNITED STATES PATENT OFFICE.

EDWARD LOUIS PEMBERTON, OF NEW HAVEN, CONNECTICUT.

ADJUSTABLE CRUSHER-HEAD.

1,089,954.

Specification of Letters Patent. Patented Mar. 10, 1914.

Application filed August 6, 1913. Serial No. 783,271.

To all whom it may concern:

Be it known that I, EDWARD L. PEMBERTON, a citizen of the United States, and a resident of New Haven, in the county of New Haven and State of Connecticut, have invented a new and Improved Adjustable Crusher-Head, of which the following is a full, clear, and exact description.

My invention relates to crusher heads which may be used for rock and other similar crushers and which are customarily mounted on a main shaft. These crusher heads are usually manufactured from cast manganese steel to provide the necessary hardness, but as crusher heads when made of this material work loose on the shaft, means must be provided for adjusting and tightening the crusher head on the shaft from time to time.

The means which I provide for adjusting and securing the crusher head to the shaft consist of a core which may be made integral with the shaft or which may be secured thereon, this core being preferably conical in shape. The mantle which forms the outer portion of the crusher head has a conical opening in which the core fits. This mantle is drawn down on the core by means of a screw, which is disposed in an orifice 30 in a lug on a key and which meshes in a threaded orifice in an inwardly disposed lug of the mantle, the lugs and the screw being disposed in a recess in the core and the key being disposed in a keyway in the core adjacent the recess. The end of the screw abuts against the core at the end of the recess and when the screw is turned, the lug of the mantle is drawn back relatively to the screw, carrying with it the mantle and the key. In this way the mantle is drawn down relatively to the core and is secured firmly thereto.

As shown in the drawings, I prefer to provide the core with four guideways and four recesses communicating therewith, the mantle having four lugs which fit in these recesses and which engage the lugs on the keys disposed in the keyways, in the manner fully disclosed in the drawings.

Still further objects of the invention will appear in the following complete description in which the preferred form of invention is disclosed in the drawings.

Similar characters of reference indicate

corresponding parts in all the views, in which—

Figure 1 is a side sectional elevation of my invention; Fig. 2 is a sectional view on the line 2—2 of Fig. 3; Fig. 3 is a sectional view on the line 3—3 of Fig. 1; Fig. 4 is a sectional view on the line 4—4 of Fig. 2; and Fig. 5 is a perspective view, showing one of the keys with its lug.

By referring to the drawings, it will be seen that the shaft 5 has a conical portion 6 around which is disposed the core member 7, this core member 7 being held down on this conical portion 6 of the shaft 5 by means of the locking nuts 8, which mesh with the thread 9 on the shaft 5. However, if desired, the core member 7 may be constructed integral with the shaft. The outer surface of this core member 7 is conical and through its conical outer surface, there are cut keyways 10 which are disposed longitudinally of the shaft 5. These keyways 10 are preferably four in number and adjacent each of the keyways 10, there is a recess 11 which extends through the outer conical surface of the core member 7. Disposed around the core member 7 there is a conical mantle 12 which has a wearing member 13, which may be replaced when desired. This conical mantle 12 with its wearing member 13 fits snugly against the conical outer surface of the core member 7 and the conical mantle 12 has inwardly extending lugs 14, which are disposed in the recesses 11 in the core member 7. There are also disposed in the recesses 11, the lugs 15 which extend from the keys 16 disposed in the keyways 10, these lugs 15 having orifices 16 through which the screws 17 are disposed, these screws meshing in threaded orifices 18 in the lugs 14, with the ends 19 of the screws abutting against the core member 7 at the ends of the recesses 11.

It will be seen that when the screws 17 are turned, they will draw the lugs 14 back from the core member 7 at the ends of the recesses 11, where the ends 19 of the screws 17 abut against the core member. In this way the mantle may be drawn back to hold it snug around the core member 7. When the lugs 14 with the mantle 12 are drawn back by the turning of the screws 17, the lugs 14 carry with them the lugs 15 thereby moving the keys 16 backward with the

mantle, so that the keys 16 will not project to prevent the movement of the mantle 12 backward. In this way the mantle 12 may be drawn back with its inner conical surface engaging the outer conical surface of the core member 7, to prevent any movement of the mantle 12 relatively to the core member 7 when the shaft 5 is rotated. The sides 10 of the lugs 14 and 15 are disposed radially and the sides of the recesses 11 are also radially disposed.

Having thus described my invention, I claim as new and desire to secure by Letters Patent:

- 15 1. In an adjustable crusher head, a core member having an outer surface, a mantle disposed around the core member and having an inner surface engaging the outer surface of the core member, one of the members 20 at its said surface decreasing in diameter in one direction, there being a recess in one of the members through its said surface, a lug on the other member extending into the recess and having a threaded orifice, and a 25 screw meshing in the threaded orifice and free for moving longitudinally of the core member for engaging the member having the recess at the end thereof.
- 30 2. In an adjustable crusher head, a conical core member, a mantle member disposed around the core member and having a conical opening, the inner surface of the mantle member and the outer surface of the core member engaging each other, a keyway and 35 a connecting recess in one of the members and extending through its said surface, a lug on the other member extending into the recess and provided with a threaded orifice, a key in the keyway and having a lug with 40 an orifice, the last-mentioned lug extending into the recess, and a screw disposed through the orifice in the last-mentioned lug and meshing in the threaded orifice in the first- 45 mentioned lug and abutting against the member having the recess at the end thereof for the purpose specified.

- 50 3. In an adjustable crusher head, a core member having an outer surface, a mantle member disposed around the core member and having an inner surface engaging the outer surface of the core member, one of the members 55 at its said surface decreasing in diameter in one direction, there being a plurality of longitudinally extending keyways spaced apart in the said surface of the core member, there being a recess in the core member communicating with each of the keyways, keys in the keyways with lugs 60 having orifices and extending into the recesses, a plurality of inwardly extending lugs on the mantle provided with threaded orifices and extending into the recesses, and

screws disposed through the orifices in the first-mentioned lugs and meshing in the threaded orifices in the second-mentioned 65 lugs and engaging the core member at the recesses for the purpose specified.

4. In an adjustable crusher head, a conical core member, a mantle member having a conical opening in which the core member is 70 disposed, there being longitudinally extending keyways spaced apart around the core member and extending through the outer surface of the core member, there being recesses extending through the outer surface 75 of the core member, one communicating with each of the keyways, lugs with threaded orifices on the mantle and extending into the recesses, screws meshing in the threaded orifices and engaging the core member at the 80 ends of the recesses, and keys free from the mantle member, the keys being disposed in the key-ways and provided with lugs engaged by the first lugs to be moved thereby.

5. In an adjustable crusher head, a conical core member, a mantle member having a conical opening in which the core member is disposed, there being longitudinally extending keyways spaced apart around the core member and extending through the 90 outer surface of the core member, there being recesses extending through the outer surface of the core member, one communicating with each of the keyways, lugs on the mantle and extending 95 into the recesses, keys in the keyways and having lugs engaging the first-mentioned lugs to be moved thereby, and means for moving the first-mentioned lugs relatively to the core member.

6. In an adjustable crusher head, a core member having an outer surface, a mantle disposed around the core member and having an inner surface engaging the outer surface of the core member, one of the members 105 at its said surface decreasing in diameter in one direction, there being in the core member a longitudinally extending keyway and a lateral recess connected therewith, the mantle having a lug with a threaded orifice 110 for moving in the keyway and from the keyway into the recess, a key for moving in the keyway to the side of the lug for holding the lug in the recess, and a screw meshing in the threaded orifice for engaging the 115 mantle at the end of the recess.

In testimony whereof I have signed my name to this specification in the presence of the subscribing witnesses.

EDWARD LOUIS PEMBERTON.
